(57) **CLAIM**

The ornamental design for a threaded insert with a replaceable nut element, as shown and described.

DESCRIPTION

FIG. 1 is an exploded top-front perspective view of a threaded insert with a replaceable nut element showing my new design;

FIG. 2 is an exploded bottom-rear perspective view thereof;

FIG. 3 is an exploded front elevational view thereof;

FIG. 4 is an exploded rear elevational view thereof;

FIG. 5 is an exploded left elevational view thereof;

FIG. 6 is an exploded right elevational view thereof;

FIG. 7 is an exploded top plan view thereof;

FIG. 8 is an exploded bottom plan view thereof;

FIG. 9 is an enlarged cross-sectional view taken along line 9-9 in FIG. 3;

FIG. 10 is an enlarged cross-sectional view taken along line 10-10 in FIG. 3;

FIG. 11 is an enlarged cross-sectional view taken along line 11-11 in FIG. 3;

FIG. 12 is an enlarged top front perspective view thereof; and,

FIG. 13 is an enlarged bottom rear perspective view thereof. The broken line showing retaining rings in FIGS. 1-8, 12, and 13 is included for the purpose of illustrating environmental structure and forms no part of the claimed design.
